UNITED STATES PATENT OFFICE.

THOMAS STEELE, OF COLUMBUS, OHIO, ASSIGNOR TO THE COLUMBUS DENTAL
MANUFACTURING COMPANY, OF COLUMBUS, OHIO.

INTERCHANGEABLE FACING AND BACKING.

Application filed September 18, 1920. Serial No. 409,949.

To all whom it may concern:

Be it known that I, THOMAS STEELE, a citizen of the United States, residing at Columbus, in the county of Franklin and State 5 of Ohio, have invented certain new and useful Improvements in Interchangeable Facings and Backings, of which the following is a specification.

Considerable difficulty has been experienced in the manufacture of interchangeable tooth facings to secure a firm anchor 10 between the facing and backing and at the same time prevent the anchor on the backing from showing through the translucent body. Posts or anchors of material cross 15 sectional area have been used but this is objectionable in that the perimeter of the post lies too close to the surface of the tooth and it is also objectionable in that it very 20 materially weakens the porcelain.

The object of my invention is to position the post a greater distance from the backing than has heretofore been thought practical and I accomplish this by making the 25 web between the post and backing wider, and by flattening or increasing the arc of the post I secure a larger area of anchorage 30 between the facing and backing and at the same time am enabled to space the perimeter of the post sufficiently far from the outer 35 surface of the tooth to prevent it from showing through the translucent body.

A further object of my invention is to so construct the post of the backing that I 40 am enabled to run or extend the post relatively nearer the incisal edge than has heretofore been deemed practical, and at the same time prevent it from showing through the translucent body, whereby I add resistance and strength to the denture by supporting it in this manner; and with these 45 and other objects in view my invention consists of the parts and combination of parts as will be hereinafter pointed out.

45 In the drawings:

Figure 1 is a vertical longitudinal section of a tooth facing embodying my invention.

Figure 2 is a similar view of the facing mounted on a backing.

50 Figure 3 is a transverse sectional view of the facing on the line 3-3 Figure 1.

Figure 4 is a transverse sectional view on the line 4-4 Figure 2.

55 Figure 5 is a front elevation of my improved backing and post.

Figure 6 is a side elevation of Figure 5. Figure 7 is a sectional view on the line 7-7 Figure 5.

Figure 8 is a detail sectional view.

The facing and backing herein disclosed 60 is primarily intended for accurately interchangeable teeth and is an improvement on the interchangeable teeth heretofore patented by me.

The reference numeral 1 designates a 65 porcelain facing which is molded with a longitudinally extending bore 2 parallel with the lingual side of the facing, one wall of the bore at 3 being bevelled on an angle toward the lingual side of the facing where- 70 by the bottom of the bore 2 terminates in a very blunt and squared point as at 4 while the side walls converge as at 3a Figure 8. A passageway or slot 5 extending into the facing from the lingual side communicates 75 with the bore 2 and is provided at its lower end with an abutment or shoulder 6 mate- 80 rially above the lower end of the bore 2 inasmuch as the slot 5 is not as long as the bore 2. Both the slot 5 and bore 2 extend 85 upwardly through the gingival end of the facing. It will be noted that the converg- 90 ing walls 3a and the bevelled end 3 of the bore all diverge from the outer surface of the tooth.

The biscuit thus molded is baked in a very high temperature and is subject to warping strains and stresses, therefore after such baking it is necessary, in order that the facings be accurately interchangeable that 95 the lingual side of the facings, and the walls of the slot be ground. This grinding proc- 100 ess is a very difficult one but I have designed tools and devices to accurately accomplish the same whereby I am enabled to grind the 105 lingual face to a perfect plane, accurately grind the walls of the slot so that each tooth made is accurately interchangeable with another, whereby upon fracture or damage to a facing another facing may be 110 readily substituted without removing the bridge or changing the backing and post.

It will be noted that by reason of the particular formation of the slot and bore, especially the bore in the facing, I am en- 115 abled to space the post a greater distance from the backing whereby I can position a greater bulk of porcelain between the post and backing than is possible with teeth as heretofore constructed and at the same time 120

avoid bringing the post too close to the outer surface of the tooth which would weaken the porcelain and in some instances make it show through the translucent body.

5 The backing 7 is a flat plate adapted for intimate contact with the perfect plane of the lingual side of the facing. The post 8 is connected to the backing by means of a flat web 9; as shown in the drawing the lower 10 end portion of the post extends below the bottom edge 10 of the web 9 and said bottom edge 10 rests on the shoulder or bottom wall 11 of the slot 5 so that the facing through the blunt bottom 4 of the bore and the comparatively wide shoulder 5 of the slot has a material bearing to resist the strains and stresses imposed upon it incident to mastication and by reason of this distribution of stresses and strains and the large amount of 20 porcelain between the backing plate 7 and post 8 the facing is much stronger and very materially less liable to split or fracture.

The increased arc of the outer face of the post with the substantially inner face of the 25 post 8 enables me to put a comparatively large amount of metal in the post, increases the bearing area of the post in the facing thereby distributing the strains and stresses throughout a larger area of the facing which 30 practically eliminates the possibility of the splitting or fracture of the facing. At its lower end the side walls of the post converge as at 11 and the inner or arcuate face of the post converges toward the backing 35 as at 12, the lower end of the post being blunt as at 13, all configuration of the post conforming to the formation of the bore 2. The converging faces 11 and 12 inclining away from the surface of the facing thus 40 enabling me to extend the post closer to the incisal edge than has heretofore been possible and at the same time not show through the translucent body thereby enabling me to obtain maximum strength in the structure 45 without sacrificing the appearance of the facing. In other words by extending the post to a point relatively lower than present day practice, I add resistance and strength to the denture by supporting it in 50 this manner, namely to a point relatively nearer the incisal edge than is now deemed practical by any present form of construction, and the comparatively larger amount of porcelain between the lingual side and the under face of the post also materially 55 increases the strength of the facing transversely.

Changes may be made in the details of construction for anterior and posterior facings within the scope of the claims.

60

What I claim is:

1. A backing for a facing having a post and a web connecting the post to the backing, the outer perimeter of the post converging at its lower end portion towards the 65 backing.

2. A backing for a denture having a post the outer face of which is converged towards the backing at its lower end portion, and a wide web connecting the post for a 70 portion of its length to and spacing it wide from the backing above said converging end.

3. A backing for a tooth comprising a flat plate, a wide web extending from and 75 at right angles to said plate, and extending from the gingival end of the plate to a point short of the incisor end of the plate, a post longer than and secured to said web and having its outer and side faces, at the lower 80 end portion below the web, converge to a blunt point.

4. A facing having a longitudinal bore extending from the gingival end toward the incisal edge and parallel with the lingual 85 side, and spaced a wide distance from the lingual side, a wide slot extending from the lingual side and communicating with said bore, the outer wall of the bore, below the bottom of the slot, converging toward 90 the lingual side.

5. A facing having a longitudinal bore extending from its gingival end, the front and side faces of which converge at the lower end of the bore, said bore being spaced a 95 material distance from the lingual side, and a slot in the lingual side communicating with said bore above the converging end of the bore and of less length than the bore.

6. An interchangeable facing having a 100 longitudinal bore extending from the gingival end to a point close to the incisal edge with its longitudinal axis substantially midway between the lingual side and the labial face, the face of the front wall of the bore, 105 near its lower end, being converged toward the lingual side, whereby a maximum amount of material is maintained between the labial face of the tooth and the converging outer face of the bore, and a slot in the lingual side communicating with but shorter than the said bore.

In testimony whereof I affix my signature.
THOMAS STEELE.
